UNITED STATES PATENT OFFICE.

CHARLES HERBERT SCOTT, OF GLOUCESTER, ENGLAND.

CONSTRUCTION OF PUNCHING AND DIE PLATES FOR INLAID-LINOLEUM MACHINES.

1,260,820.

Specification of Letters Patent. Patented Mar. 26, 1918.

Application filed December 10, 1914. Serial No. 876,594.

To all whom it may concern:

Be it known that I, CHARLES HERBERT SCOTT, a subject of the King of Great Britain, residing in Gloucester, England, have 5 invented certain new and useful Improvements in the Construction of Punching and Die Plates for Inlaid-Linoleum Machines, of which the following is a specification.

This invention relates to apparatus for 10 punching or stamping the tesserae of different solid-color linoleums required in the manufacture of inlaid linoleum, and it is designed to provide punch and die plates which may be altered to produce tesserae of 15 different or differently-arranged, patterns; the invention being specially devised for use in linoleum machines of the type shown and described in my prior Patent, No. 1,173,875, issued February 29, 1916.

20 In machinery of the character specified, it is customary, as explained in my aforesaid patent, to utilize, in addition to a templet, a flat, metal die or pattern plate having apertures through or into which the tesserae 25 are stamped by punches on a punch plate and deposited in position on the canvas backing; and it is also usual to rigidly secure the punches to a foundation plate or other carrier of some sort. In consequence, 30 when it is desired to change the pattern, it becomes necessary not only to provide a new punch plate whereon the punches are arranged in accordance with the new pattern, but also to construct a complete new die 35 plate having its openings or apertures conforming to such pattern, a fresh templet being likewise required, so that the proceeding, as a whole, involves considerable time and trouble, as well as expense.

40 The present invention has been designed with the object of overcoming this defect by constructing both the die plate and the punch plate of a number of similar symmetrical blocks, which are mounted upon 45 suitable foundation plates in such a way as to be capable of re-arrangement in order to conform to different patterns. According to the invention, the blocks or punches are solid, and those on the die plate are so arranged 50 that the spaces left between them exactly correspond in size, shape and relative positions to the tesserae of any single color in a finished linoleum of the particular pattern to be produced. Consequently, 55 these spaces take the place of the openings or apertures of the die plates

formerly used; and since the blocks are capable of interchangeable arrangement on their carrier plate, it will be apparent that by merely changing the relative positions 60 of the blocks, the size, shape and positions of the spaces will be correspondingly varied, so that the same set of blocks and carrier can thus be used for any number of different patterns, and the expense of constructing a separate plate for each pattern as has heretofore been necessary, is completely 65 obviated. As regards the punch plate, the blocks thereon, hereinafter termed the punch blocks, enter into the space between those 70 on the die plate, just as in the former construction they entered the openings in the die plate, when the two plates are moved toward each other; it being understood, of course, that the punch blocks are capable 75 of arrangement on their carrier in the same way as the die blocks, with the exception that they are positioned to stamp or punch out the tesserae and force them into the above-mentioned spaces, so that the two sets 80 of blocks have, in a sense, a complementary arrangement.

In addition to the foregoing, the invention also resides in the provision of devices 85 for ejecting the tesserae from the spaces between the die blocks and depositing them on the canvas backing in the exact positions and relations required for the finished linoleum; the ejectors, like the die and punch blocks, being capable of variable arrangement on 90 the die block carrier, to conform to the pattern being followed.

Other and further features and advantages will present themselves as the description proceeds, reference being had to the 95 accompanying drawing, in which one embodiment of the invention is illustrated.

In said drawing:

Figure 1 is a vertical cross-section of a pair of co-operating punch and die plates 100 constructed according to the invention, the section being taken on line 1—1, Fig. 2.

Fig. 2 is a sectional plan view of the die plate, taken on line 2—2, Fig. 1.

Fig. 3 is a fragmental perspective view, 105 partly in vertical section, of a grid which may be utilized in conjunction with the die plate.

Fig. 4 is a detail view, largely diagrammatic, showing a die block fitted in one of 110 the pockets of the aforesaid grid.

Referring more particularly to said draw-

ing, there is shown an arrangement adapted to produce a pattern composed of squares or combinations of squares, though such showing is, of course, purely arbitrary and 5 is given merely by way of example. The die and punch plates represented are primarily designed for use in, or as a part of, the apparatus disclosed in my aforesaid Patent, No. 1,173,875, in place of the corresponding plates therein comprised, as previously stated, reference to said patent being made in order to connect it with the present invention and in order that it may be referred to for a complete description of 10 the apparatus as a whole, and its manner of operating.

The two plates represented in Fig. 1 are arranged horizontally in superposed relation, and are adapted to be brought together 20 to effect the punching operation by means of the mechanism shown in the patent, or by other suitable devices, the upper or die plate constituting the stationary element and the lower or punch plate the companion 25 movable element, as in the patented construction. Each of said plates or elements consists of a flat foundation plate or carrier, and a series of blocks connected thereto and capable of re-arrangement accordantly with 30 the various patterns to be produced, and in addition the die plate embodies a set of interchangeable ejectors, all hereinafter described in detail.

In the case of the die plate, the foundation plate or carrier is indicated at *a*, and is formed with transverse openings *a'*, which are spaced apart at regular intervals. The die blocks *d* are or may be solid, and, in the construction illustrated, are square; 40 though they may have other shapes, for instance, right-angled triangles, the two remaining angles of which are 45° each, in which instance either square or triangular patterns may be produced. These blocks 45 are arranged against the under face of the foundation plate, and are retained in place by means of their upstanding shanks *d'*, which extend through the holes or openings *a'* and are fitted with nuts *a''*, the latter being tightened against the upper face of the foundation plate. The construction of the punch plate is substantially the same as that of the die plate, in so far as the said punch plate comprises a foundation plate *c* formed 50 with holes *c'* arranged similarly to the holes *a'* in the plate *a*, and a series of square blocks *g* similar to the die blocks *d* and having threaded shanks *g'* which are inserted through the holes *c'* and fitted with retaining 55 nuts *c''*, the blocks and nuts being arranged, respectively, against the upper and lower faces of plate *c*.

As above explained, the sets of die and punch blocks *d* and *g* are disposed upon 60 their respective foundation plates or car-

riers *a* and *c* in such a way as to conform to the pattern undergoing production; the spaces left between the die blocks exactly corresponding in size, shape and relative position to the tesserae of any single color 70 in the finished linoleum, while those between the punch blocks correspond in like manner to the shape, size and position of the die blocks, so that when the two plates are brought together, the two sets of blocks will 75 coact in the usual way to effect the stamping or punching operation and the stamped-out tesserae *h*, (Fig. 1) will be forced into the spaces between the die blocks, just as in the patented apparatus they were forced 80 into the apertures in the die plate. See Fig. 4 of the patent.

In carrying out the stamping operation, the sheet of solid color linoleum is placed upon a templet *b* (Fig. 1), which is located 85 between the die and punch plates and is directly associated with the latter plate. This templet corresponds to the guide plate of the patented apparatus and is, of course, provided with openings arranged in precisely the same manner and having exactly 90 the same size and shape as the punch blocks, so that it may be fitted over said blocks in the way shown in Fig. 1 and yieldingly supported above the foundation *c* in such a position that its upper face is normally flush with the upper faces of the punch blocks. In actual practice, a separate templet is required for each pattern; and in assembling 95 the parts, after a pattern has been selected, 100 the corresponding templet is laid over the foundation plate and the blocks *g* then inserted through the openings in the templet and fixed to the foundation plate, after which the die blocks *d* are fixed to 105 their plate *a* in the proper positions. Hence the punch blocks are forced to move through the openings in the templet during the punching operation, owing to the yielding support provided for the templet, the edges 110 of the openings in the latter serving to scrape or remove from the sides of the punch block any linoleum debris which may have adhered thereto at such time.

In order to remove the tesserae *h* from the 115 spaces between the die blocks, and to deposit them in the precise position required upon the canvas backing, the above-mentioned ejectors are provided. These ejectors are preferably in the form of block-like 120 plungers *e*, the shanks or stems of which are inserted upward through the holes *a'* in the foundation plate *a* and are encircled by expansible coil springs *f*, the latter acting 125 against nuts provided upon said stems and thus serving to maintain the plungers normally in raised, inoperative position, as represented in Fig. 1. Any suitable means or mechanism may be employed to depress the plungers and thereby eject the tesserae; but 130

as such forms no part of the present invention, illustration thereof is considered unnecessary.

It has been found from experience that the tesserae cut from a sheet or blank of solid-color linoleum have a tendency to expand somewhat, so that it is frequently advisable to employ punches which will cut them slightly smaller than the size actually required in the finished linoleum. In this case, as shown in Figs. 3 and 4, the foundation plate *a* of the die plate may be furnished on its lower face with a grid or the like *i*, which is formed of narrow intersecting strips or plates of steel so arranged as to provide pockets or recesses of the size of the die blocks *d*; and the latter may be inserted into some of these pockets to fill them up, and to strengthen the grid though this is not always necessary. The depth of the pockets is preferably the same as the height of the die blocks *d*, so that the free edges of the pockets and the blocks will be flush. The punch blocks *g* are caused to enter the opposite pockets during the cutting operation, and in such case the cutting action will be effected by the movement of the punch blocks past the edges of said pockets; but only the edges of those pockets which the punch blocks enter will be enabled to exert a cutting or shearing action, the remaining edges having no effect whatever upon the linoleum sheet or blank. The punch plate remains exactly the same, excepting that the sides of the punch blocks, or their projections, do not connect, but leave a space between them equal to the thickness of the strips of which the grid is made.

Having thus described my said invention and the best means I know for carrying the same into practical effect, I claim:—

1. A die plate for inlaid linoleum machines, comprising: a foundation plate; and a series of symmetrical blocks arranged on said foundation plate in such a manner that the spaces left between them exactly correspond in size, shape and relative position to the tesserae of any single color in a finished linoleum of the particular pattern to be produced; said spaces being designed to directly receive therein the tesserae cut from a strip of linoleum of such color during the cutting operation, whereby the said tesserae may be deposited from said die plate directly upon the backing strip in the precise arrangement required for the finished linoleum.

2. A die plate for inlaid linoleum machines, comprising: a foundation plate; and a series of symmetrical blocks arranged on said foundation plate in such a manner that the spaces left between them exactly correspond in size, shape and relative position to the tesserae of any single color in a finished linoleum of the particular pattern to be produced; said spaces being designed to directly

receive therein the tesserae cut from a strip of linoleum of such color during the cutting operation, whereby the said tesserae may be deposited from said die plate directly upon the backing strip in the precise arrangement required for the finished linoleum; said foundation plate having means whereby the arrangement of the blocks thereon may be varied, so as to provide for variation of the pattern. 75

3. A die or punch plate for inlaid linoleum machines, comprising: a foundation plate provided with holes which are regularly spaced from one another; and a series of symmetrical blocks having stems for interchangeable engagement in said holes, so as to permit their arrangement according to different predetermined patterns; said blocks, when so arranged, or the spaces between them, exactly corresponding in size, shape 80 and relative position, to the size, shape and relative position of the tesserae of any one color in a finished linoleum of the particular pattern to be produced. 85

4. In an inlaid linoleum machine, means 90 for cutting or stamping the tesserae of solid-color linoleum, comprising: a die plate consisting of a foundation plate having a series of symmetrical blocks arranged thereon in such a manner that the spaces left between them correspond in size, shape and relative position to the tesserae of any single color in a finished linoleum of the particular pattern to be produced; and a punch plate consisting of a foundation plate having mounted 95 therein a series of symmetrical cutting blocks whose arrangement is such that the outline of said cutting blocks coincides with that of said spaces, so that the former will project into the latter during the cutting 100 operation and will introduce the cut or stamped out tesserae thereinto, whereby the said tesserae may be deposited from said die plate directly upon the backing strip in the precise arrangement required for the finished linoleum. 105

5. In an inlaid linoleum machine, means 110 for cutting or stamping the tesserae of solid-color linoleum, comprising: a die plate consisting of a foundation plate having a series of symmetrical blocks arranged thereon in such a manner that the spaces left between them, correspond in size, shape and relative position to the tesserae of any single color in a finished linoleum of the particular pattern to be produced; and a punch plate consisting of a foundation plate having mounted 115 therein a series of symmetrical cutting blocks whose arrangement is such that the outline of said cutting blocks coincides with that of said spaces, so that the former will project into the latter during the cutting operation and will introduce the cut or stamped out tesserae thereinto, whereby the said tesserae may be deposited from said die 120 plate. 125

plate directly upon the backing strip in the precise arrangement required for the finished linoleum, each of said foundation plates having means whereby the arrangement of the blocks thereon may be varied, so as to provide for variation of the pattern.

6. In an inlaid linoleum machine, a die plate comprising: a foundation plate; a series of symmetrical blocks carried by said 10 foundation plate and arranged thereon in such a manner that the spaces left between them will correspond in size, shape and relative position to the tesserae of any single color in a finished linoleum of the particular 15 pattern to be produced; and a grid carried by said foundation plate and having symmetrically-arranged recesses conforming to the size and shape of said blocks, so as to receive the latter therein and be filled thereby; the remaining recesses in said grid being designed to directly receive therein the tesserae cut from a strip of such color during the cutting operation, whereby the said tesserae may be deposited from said die 20 plate directly upon the backing strip in the precise arrangement required for the finished linoleum.

7. In an inlaid linoleum machine, a die plate comprising: a foundation plate; a 30 series of symmetrical blocks carried by said foundation plate and arranged thereon in such a manner that the spaces left between them will correspond in size, shape and relative position to the tesserae of any single color in a finished linoleum of the particular pattern to be produced; and a grid carried by said foundation plate and composed of thin, intersecting plates providing symmetrically-arranged recesses conforming to 35 the size and shape of said blocks, so as to receive the latter therein and be filled thereby; the remaining recesses in said grid being designed to directly receive therein the tesserae cut from a strip of such color during 40 the cutting operation, whereby the said tesserae may be deposited from said die plate directly upon the backing strip in the precise arrangement required for the finished linoleum.

8. In an inlaid linoleum machine, a die plate comprising: a foundation plate; a grid mounted on the face of said foundation and having symmetrical openings; and a series 50 of symmetrical blocks adapted to conformably fit said recesses and to be variably inserted therein and arranged in such a manner that the spaces between the recesses occupied by said blocks will correspond in size, shape and relative arrangement to the 55 tesserae of any single color in a finished strip of linoleum of the particular pattern to be produced, said spaces being designed to di- 60

rectly receive therein the tesserae cut from a strip of such color during the cutting operation, whereby the said tesserae may be deposited from said die plate directly upon the backing strip in the precise arrangement required for the finished linoleum.

9. In an inlaid linoleum machine, a die plate comprising: a foundation plate; a 70 series of symmetrical blocks arranged on said foundation plate in such a manner that the spaces left between them exactly correspond in size, shape and relative position to the tesserae of any single color in a finished 75 linoleum of the particular pattern to be produced, said spaces being designed to directly receive therein the tesserae cut from a strip of linoleum of such color during the cutting operation; and plungers mounted in said 80 spaces to eject the tesserae from the same and deposit them directly upon the backing strip in the precise arrangement required for the finished linoleum.

10. In an inlaid linoleum machine, a die 85 plate comprising: a foundation plate; a series of symmetrical blocks arranged on said foundation plate in such a manner that the spaces left between them exactly correspond in size, shape and relative position 90 to the tesserae of any single color in a finished linoleum of the particular pattern to be produced, said spaces being designed to directly receive therein the tesserae cut from a strip of linoleum of such color during the 95 cutting operation; and plungers mounted in said spaces to eject the tesserae from the same and deposit them directly upon the backing strip in the precise arrangement required for the finished linoleum; said foundation plate having means whereby the arrangement of both the blocks and the plungers may be varied, so as to provide for 100 variation of the pattern.

11. A die or punch plate for inlaid linoleum machines, comprising: a foundation plate; and a series of symmetrical blocks arranged on said foundation plate in such a manner that either said plates, or the spaces between them, correspond exactly in size, 110 shape and relative position to the tesserae of any single color in a finished linoleum of the particular pattern to be produced; said foundation plate having means whereby the arrangement of the blocks thereon may be 115 varied, so as to provide for variation of the pattern.

In testimony whereof I have signed my name to this specification in the presence of two subscribing witnesses.
